(57) **CLAIM**

The ornamental design for a bottle, as shown and described.

DESCRIPTION

FIG. 1 is a front elevational view of a bottle showing our new design, the opposite rear elevational view being identical;

FIG. 2 is a side elevational view of the bottle depicted in FIG. 1, representing a partial rotation of the bottle about its vertical center axis from the elevational view depicted in FIG. 1, the opposite side elevational view being identical; FIG. 3 is a top plan view of the bottle depicted in FIG. 1; and,

FIG. 4 is a bottom plan view of the bottle depicted in FIG. 1.
